UNITED STATES PATENT OFFICE.

PETER WILLIAM SCHROEDER, OF CHICAGO, ILLINOIS, ASSIGNOR OF ONE-FOURTH TO
ALFRED L. REED, OF ANDERSON, INDIANA.

COIN-CONTROLLED MECHANISM.

1,084,563.

Specification of Letters Patent.

Patented Jan. 13, 1914.

Application filed January 4, 1909. Serial No. 470,684.

To all whom it may concern:

Be it known that I, PETER WILLIAM SCHROEDER, a citizen of the United States, residing at Chicago, in the county of Cook 5 and State of Illinois, have invented certain new and useful Improvements in Coin-Controlled Mechanism, of which the following, taken in connection with the drawings, is a description.

10 My invention has for its object the production of a coin controlled mechanism, and in the present instance embodies the use of such mechanism with a revolvable carrier containing articles to be vended, said carrier also 15 containing display advertising cards which are rotatable with the carrier, the purpose being to partially revolve the carrier each time a coin is dropped in the machine, and with each revolution to display a different 20 advertising card.

Another object of my invention is to provide a vending machine which is simply constructed and easily operated, and which contains in a display case the articles to be 25 vended, which may be matches, gum, postage stamps, post cards, or any small article for which there is a demand.

A further object of my invention is to provide a machine which is automatically 30 locked against operation until a coin is deposited in the machine and the operating lever moved, also to lock the machine against a double operation with only one coin, all of 35 which is described in the following specification.

In the embodiment of my invention which is shown in the drawings, I have illustrated a machine showing a display carrier, having a plurality of stacks or receptacles arranged 40 vertically, with coin controlled mechanism for rotating this carrier a portion of a revolution at each operation, and mechanism for preventing the carrier from rotation except in one direction.

45 Various modifications in detail and touching the construction and arrangement of the different parts of the machine will suggest themselves to persons skilled in the construction and use of this class of machinery, 50 but my invention is not limited in these regards, as the form shown is but an embodiment of the invention.

In the drawings Figure 1 is a side elevation of the complete machine; Fig. 2 is a transverse sectional view taken on line 2—2 55 of Fig. 1; Fig. 3 is a vertical sectional view through the center of the machine, the stack being broken; Fig. 4 is a view taken on line 4—4 of Fig. 3; Fig. 5 is a sectional view taken on line 5—5 of Fig. 4; Fig. 6 is a view 60 of the coin actuated mechanism taken on line 6—6 of Fig. 4; Fig. 7 is a detailed view taken on line 7—7 of Fig. 4; Fig. 8 is a detailed view of the coin holder.

In the accompanying drawings A represents a casing, which may be of wood or metal and ornamented in any desired way, and which contains the operative mechanism and the money drawer.

A' is an upright casing preferably of 70 transparent material, which casing contains the carrier having the articles to be vended, and the cards for display advertising.

Suitably mounted in the casing A is a stationary frame B to which is secured the 75 operative mechanism. Rising from the center thereof is a vertical spindle B' which extends through the top of the transparent casing A' and which is secured in place by the screw a.

C is a revolvable carrier supported on the spindle B' and which carries a plurality of stacks b, b, b, b, arranged at right angles to each other around said spindle. The front of each of these stacks is left open 85 so that the articles A³ to be vended are exposed through the case. Projecting from the outer corners of each of the stacks b are clips b' by means of which the advertising cards b² are held in place. Surmounting 90 the stacks and supported by the spindle B' is a cone shaped frame, which is exposed through the transparent casing A' upon which advertising matter is displayed.

Referring now to the operative mechanism: Rigidly secured to the spindle B is a sleeve c and carried thereby is an intermittently revolving ratchet wheel D, which is provided with a suitable number, in this case four, corresponding equidistant projections d. Supported above the stationary frame B³ are the receptacles b, b, b, b which are adapted to be rotated on a track which supports the contents of the receptacles.

Above the delivery chute this frame B³ is provided with an opening through which one of the packages in each receptacle will drop onto the shelf a³ as said receptacle is brought into delivery position. The supporting frame B is provided upon one side thereof with an opening B² through which the article to be vended drops to the delivery chute B⁴. Supported on the frame B is a movable plate D', to which is secured the arm D³, having thereon a shoulder d' which is adapted to contact with one of the projections d on the ratchet wheel D upon each operation of the machine. A spring D⁴ secured to said arm and to the frame B holds the arm in contact with the ratchet wheel D. A second arm E is secured to the stationary frame B, and projects into the path of the ratchet wheel D upon the side opposite to the arm D³. This arm is held in contact with the wheel D under tension of the spring E'. Carried by the movable plate D' is a rack bar F, and engaging therewith is the pawl f, pivotally secured to the stationary frame B, which pawl is held in normal position by the spring f'. The purpose of this rack bar and pawl will be hereinafter explained. Carried by the movable plate D' and extending through a slot e in the case A is the operating lever G. Surrounding the slot e is a plate e' having a thumb piece e². Secured in bearings e³, extending from the lower side of the stationary frame B is a rod G' upon which the movable plate D' is supported, said plate operating against the tension of the spring G² which is secured at one end to the stationary frame B and tends to return the plate to normal position after each operation.

Secured to the stationary frame and extending parallel with the rod G' is a coin chute, which I will now describe.

H is the coin chute which is provided with a downwardly inclined, upwardly opening slot h which is coincident with the slot h' in the casing A. The coin chute is formed of two parallel sections h², h³, one of which has an inner rib h⁴ upon which the coin rolls to the lower end of the incline. Extending into each of the sections h², h³ of the coin chute and beneath the rib h⁴ is an open ended slot h⁵, said slot opening toward the operating lever G. Pivotally secured to the inside of the section h² of the coin chute is a movable member K which is held in normal position by the spring k. The free end k of this movable member is bent at right angles to itself and extends beneath the extreme lower end of the coin chute and upon which the coin drops as it is rolled down the chute. The upper edge of this member K is provided with a projecting shoulder k², which extends into the path of a projection k³, carried by the movable plate D' and locks

the machine against operation until a coin 65 is dropped into the chute.

The operation of the machine is as follows: When the machine is ready for operation the receptacles are filled with the articles to be vended with one package on the 70 shelf a³ ready for delivery. A coin H' is dropped into the chute H which rolls down the incline until it drops against the projection k'. The weight of the coin has depressed the movable bar K sufficiently to 75 move the shoulder k² out of the path of the projection k³. The operator then moves the lever G to the left and carries the projection over the coin H' pressing downwardly thereon until it falls out of the coin chute and 80 rolls into the coin box H² located inside of the casing A. The movement of the lever G has carried with it the movable plate D' and the arm D³ until the projection d' thereon engages one of the ratchets d upon the 85 wheel D and by this engagement has given said wheel a one quarter turn, which has brought one of the receptacles b over the opening above the shelf a³, the movable plate D' has been brought forward into contact with the article on the shelf a³ and pushed it into the delivery chute B³, which is inclined, and down which the article will drop by gravity to the end of the chute where it may be picked up by the purchaser. 95 As the article which was on the shelf a³ is being pushed out of the way, another article from the stack directly above the chute will be dropped into its place to be ready for the next operation of the machine.

When the machine is not in operation, the rack bar F and pawl f remain in the position shown in Fig. 4, when a coin has been placed in the machine and the lever moved to the left as far as it will go, the pawl f passes 105 over the rack bar without engagement with the teeth, but if the lever is moved only part way to the left the pawl engages the rack bar and prevents the lever from being returned to normal position until the machine has completed an operation. This prevents the possibility of two articles being delivered when only one coin has been placed in the machine.

I claim:

In a vending machine, the combination of a casing, a stationary frame supported in said casing and having an opening therethrough, a shelf beneath said opening upon which each successive article to be vended is 120 temporarily deposited, a bottomless rotatable carrier mounted upon a spindle supported in said frame, said carrier having a plurality of vertically arranged compartments adapted when the carrier is rotated to 12 pass over the opening in said frame, a ratchet on said spindle, ejecting mechanism secured to said frame and in proximity to

the aforesaid opening and coacting with the aforesaid ratchet, a lever operating said ejecting mechanism to simultaneously move the carrier a partial revolution and eject the article deposited on the aforesaid shelf, and means for locking said mechanism against operation, substantially as described.

In testimony whereof I have signed this specification in the presence of two subscribing witnesses.

PETER WILLIAM SCHROEDER.
